UNITED STATES PATENT OFFICE.

HENRY M. COLLESTER, OF GARDNER, MASSACHUSETTS.

DESIGN FOR CANE FABRIC.

SPECIFICATION forming part of Design No. 26,550, dated January 19, 1897.

Application filed December 11, 1896. Serial No. 615,407. Term of patent 7 years.

To all whom it may concern:

Be it known that I, HENRY M. COLLESTER, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists of the arrangement of parallel companion stripes *a a* and the intersecting stripes *b*, all of a contrasting color from the body of the fabric, the stripes *a* being interrupted upon their opposing margins to show the body of the fabric as marginal checks, the stripes *b* being interrupted to appear as rows of checks.

f represents a piece of cane fabric bearing my design, which consists of the parallel companion stripes *a a* and the intersecting stripes *b*, all of a contrasting color from the body of the fabric. The stripes *a* are interrupted upon their opposing margins to show the body of the fabric as marginal checks. The stripes *b* are interrupted to appear as rows of checks.

I claim—

The design for cane fabric, as herein shown and described.

In testimony whereof I have signed my name to this specification, in the presence of two subscribing witnesses, this 30th day of November, A. D. 1896.

HENRY M. COLLESTER.

Witnesses:

EDWARD G. WATKINS,
THATCHER B. DUNN.
